(57) **CLAIM**

The ornamental design for a bag dispenser for pet refuse, as shown.

DESCRIPTION

FIG. 1 is a front and side perspective view of a bag dispenser for pet refuse embodying my new design;

FIG. 2 is a front elevational view thereof;

FIG. 3 is a rear elevational view thereof;

FIG. 4 is a left-side elevational view thereof; the rights-side elevational view being a mirror image;

FIG. 5 is a bottom plan view thereof; and,

FIG. 6 is a top plan view thereof.
